UNITED STATES PATENT OFFICE.

WILLIAM D. GHERKY, OF PHILADELPHIA, PENNSYLVANIA.

GRINDING-MACHINE.

1,161,653.

Specification of Letters Patent. Patented Nov. 23, 1915.

Application filed March 24, 1913. Serial No. 756,531.

To all whom it may concern:

Be it known that I, WILLIAM D. GHERKY, a citizen of the United States, residing at Philadelphia, in the county of Philadelphia and State of Pennsylvania, have invented 5 certain new and useful Improvements in Grinding-Machines, of which the following is a specification, reference being had therein to the accompanying drawing.

10 The rail grinding machine of my invention is of the type now commonly used on the tracks of electrical and steam railways and operating from the track to remove defects in the rails. While of this particular 15 type however, it will be apparent to those skilled in the art upon full understanding of my invention, that it may be used in connection with other types of machines, arranged to travel upon and operate from 20 trackways of any description.

The characteristic feature of this machine is the guidance of the grinding element with respect to the tram portion of the rail as distinguished from the head. In the embodiment of the machine which I illustrate and describe herein, the grinding element is supported by travelers which engage and travel upon the tram of the rail. It is a well-known fact that while the head of the 25 rail and the side of the groove are worn down with great resulting irregularity of surface, the tram portion of the rail remains substantially as true as when the rail was first laid. Even at the joints this portion of 30 the rail is preserved substantially in its original condition, the distortion, wear and beating down being confined wholly to the head of the rail. Thus it is apparent that the tram portion of the rail constitutes a 35 permanently true surface of reference for the guidance of rail dressing elements operating upon any part of the rail whatsoever.

40 Of the drawings: Figure 1 is a side elevation of the machine of my invention; Fig. 45 2 is a plan view thereof arranged for convenience at right angles to Fig. 1, Figs. 3 and 4 are transverse sections taken at the rail joints of two forms of rails in common use, and Figs. 5 to 8 are diagrammatic views 50 illustrating the means for guiding rail dressing elements heretofore employed.

55 Heretofore four principal means of guiding have been resorted to as shown in Figs. 5 to 8. Fig. 5 shows the early means of supporting the grinding wheel from track wheels on opposite sides thereof and travel-

ing upon the head of the rail. The result in the case of the corrugated or otherwise defective rail as illustrated, is obvious. The irregularities of the surface of the rail acting through the point supports constituted by the wheels effect correspondingly irregular movements of the rail dressing element. By using extended supports in the form of sliding rail shoes as shown in Fig. 6, the effect of the irregularities in the head of the rail has been in large measure though not wholly overcome. The length of the rail shoe is made such as to bridge over the average depression or other defect as illustrated. The means shown in Fig. 7 is still more effective, being constituted by a reciprocating dressing element of a length greater than any wave length or corrugation to be ground out. The reciprocating element illustrated is of the type commonly used in a number of machines previously invented by me, and comprises a plurality of grinding bricks arranged in tandem in a common reciprocating frame. The traveler shown in Fig. 8 has also been used in the manner of the rail shoe of Fig. 6, the essential difference between the rail shoe of Fig. 6 and the traveler of Fig. 8 being that the traveler is provided with a plurality of rollers through which engagement is made with the trackway. The advantage in this is that the friction and wear of the rail shoe are eliminated. Obviously were the head of the rail on opposite sides of any given defect free from defects, the arrangements of Figs. 6 to 8 and others for the same purpose would be wholly unnecessary. The tram of the rail as previously stated is wholly free from such defects.

95 In Fig. 3 I have shown a grooved rail, and a rail dressing element W and a guiding element S therefor engaging respectively the head H of the rail and the tram T. The guiding element illustrated is a flanged wheel, the flange F of which is on the out-board side of the wheel instead of the in-board side as usual. The flange F substantially fits within the groove G of the rail but does not reach the bottom thereof by some little distance. Thus accumulation of materials in the groove G does not affect the continuous travel of the guide S upon the tram T. The thickness of the flange F will not be so great as to jam within the groove G or to be affected by the irregularities in the side thereof. The tread R of the guide

S is of relatively small width and projects but slightly if at all past the tram T, whereby the guide S is likewise unaffected by the irregularity or projections of surfaces on the inside of the tram T.

Fig. 4 shows practically the same arrangement as Fig. 3. The essential difference is that the rail is of the flat tram pattern, and the guiding element S has its 10 engaging face formed to suit.

Having this understanding of the characteristic feature of my invention, its embodiment in a complete machine for commercial use will be quickly apprehended. 15 The embodiment which I show in Figs. 1 and 2 is in the machine forming the subject matter of my Patent No. 1,096,005, dated May 5, 1914. For a full description of the details thereof and its operation reference 20 may be made to this patent. Stated briefly for present purposes, the machine comprises a main frame 1 rectangular in shape and supported from the trackway by wheels 18 at one end thereof and travelers 20 of the 25 type shown in Fig. 8 at the other end thereof. On each side and adjacent in each case to the traveler 20 on that side, the frame supports rotary grinding wheels 80 in a position to operate upon the heads of the 30 rails. These grinding wheels are mounted upon auxiliary and adjustable frames 86, 84 and in operation are driven continuously by an electric motor 9. Also driven by the 35 motor 9 through gears 11, 12, 25, 26, 32, 33, 56, 55, is a feeding and timing device constituted by gears 53, 51, rock shaft 52, and connections 49, 46, 43, 38, 35 of the rock shaft 52 with a clutch on transverse shaft 22. Clutch 35^a is reversed at intervals the 40 length of which is determined by the adjustment of link 46 with respect to arm 49 of shaft 52. This reversal of clutch 35 not only reverses shaft 22 and hence the direction of travel of the machine along the 45 track, (the machine being driven through wheels 18 and the gearing afore-mentioned), but also determines the oscillation and the period thereof of shaft 52 of the timing device (which is also driven through gears just 50 mentioned).

Shaft 52 is connected by arm 109 and link 107 with the oscillatable shaft 103 which is provided with cam arms 102 engaging directly the projections 86^a from the 55 adjustable frames 86 supporting the grinding element. The frames 86 are pivotally supported at one end on shafts 88 and are biased upwardly at the other ends against cam arms 102 by means of suitable springs 60 not shown. The result is that the frames 86 are moved up and down as the machine travels back and forth along the track, and in direct accordance with the degree and the period of oscillation of shaft 103. In the 65 aforesaid patent the wheels 18 and the

travelers 20 are shown as engaging and traveling upon the head of the rail, the length of travelers 20 and the proximity of the grinding 80 thereto being relied upon to eliminate the effect of the irregularities of 70 the head of the rail upon the guidance of the grinding element 80. Referring particularly to Fig. 2, it will be seen that both the grinding wheels 18 and the travelers 20 are mounted in a plane inside of the plane 75 of the grinding wheels instead of in the same plane, and that they engage and travel upon the tram of the rail as shown in Fig. 3. In Fig. 2 the rails are indicated by dotted lines and the parts thereof let- 80 tered similarly to the parts in Fig. 3.

My invention is capable of many modifications without departing in any wise from its generic spirit. Such modification for instance would be constituted by the substitution of any of the forms of supports shown in Figs. 5 and 6 for the travelers 20 having the rollers 20^a. So also since both the travelers 20 and the wheels 18 engage the tram of the rail, the grinding elements 90 80 may be removed from the travelers 20 any desired distance without affecting the accuracy of the grinding. On the other hand the supports 20 may be placed in position to travel upon the tram of the rail, 95 while the driving wheels 18, which are somewhat remote from the grinding element, may engage the head of the rail, if it be found that greater tractive effect is necessary than can be obtained upon the tram. 100 It should be particularly noted that in such case the grinding elements should be placed closely adjacent the travelers 20, and should depend thereon, so that the full benefit of guidance from the tram will be obtained. 105 The means of driving the machine actually constitute no direct part of the invention, and the latter will be fully satisfied if the supporting means for the grinding elements travel entirely free of the head of the 110 rail which is to be ground, and are supported upon the tram.

Having thus described my invention what I claim and desire to secure by Letters Patent is:

1. In a machine of the class described, a rail dressing element, and a guide therefor, with means connecting the two in offset relation, so that the dressing element will engage and operate upon the head of a rail, and the guide will travel exclusively upon the tram of the rail, and means for causing the parts to travel along the rail in this relation.

2. In a machine of the class described, a frame, a dressing element supported on said frame, and adapted to engage the head of a rail, means for driving said frame and its dressing element along the rail, and a guide for the dressing element adapted to engage and travel upon the tram of the rail exclu- 130

sively, whereby the cut of the dressing element is determined with reference to the unworn tram, and without reference to the surface configuration of the rail head upon which it operates.

3. In a machine of the class described, a frame, a rail-head dressing element supported upon said frame, and a track support for the frame and element comprising a flanged guide offset from the dressing element so as to engage and travel exclusively upon the tram portion of the rail entirely free from the head thereof.

4. In a machine of the class described, a frame, a rail-head dressing element, and a flanged guide supporting the frame and said element and offset from the latter so as to engage and travel upon the tram of the rail exclusively, with its flange engaging one side of said tram.

5. A machine of the class described comprising a frame adapted to span a trackway, a rail dressing element supported on said frame in position to operate upon the head of one rail of the trackway, and trav-

elers supporting said frame on opposite sides of said dressing element each engaging and traveling exclusively upon the tram portion of one of the rails.

6. A rail grinding machine comprising a frame, a grinding element supported on said frame and adapted to engage the head of a rail, and a guide supporting said frame and offset from the grinding element so as to travel exclusively upon the frame of the rail.

7. A rail grinding machine comprising a frame, a grinding element supported thereon in position to engage the head of a rail, supporting and guiding means connected to the frame and offset from the grinding element so as to engage and travel exclusively upon the tram of the rail, and driving wheels also connected with the frame.

In testimony whereof I affix my signature in presence of two witnesses.

WILLIAM D. GHERKY.
